CLAIM

The ornamental design for a wall trim and molding removal tool, as shown and described.

DESCRIPTION

FIG. 1 is a front perspective view of a wall trim and molding removal tool showing my new design;

FIG. 2 is a top view of the wall trim and molding removal tool;

FIG. 3 is a right side view of the wall trim and molding removal tool; and,

FIG. 4 is a perspective view of the bottom of the wall trim and molding removal tool.

The broken lines in the drawings illustrate a handle that forms no part of the claim.
